UNITED STATES PATENT OFFICE.

EDWARD POOLE, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,899, dated June 4, 1872.

To all whom it may concern:

Specification describing a new and original Design for a Carpet, invented by EDWARD POOLE, of Halifax, in the county of York, England.

The accompanying photograph fully illustrates my invention.

This invention relates to a new design for carpets and other fabrics in which series of rectangular figures are arranged. The larger of these figures has a serrated border with a cross therein, and projecting leaves at its corners. In the middle of this larger figure is a floral wreath around a landscape. The smaller rectangles contain wreaths and geometrical figures, as shown.

I claim as my invention—

The design for a carpet, as shown.

EDWARD POOLE.
